Inventor:

Herman Leineweber,
By Dyrnforth & Dyrnforth,
Attn:

UNITED STATES PATENT OFFICE.

HERMAN LEINEWEBER, OF CHICAGO, ILLINOIS, ASSIGNOR, BY DIRECT AND MESNE ASSIGNMENTS, TO NICHOLAS HEINSEN AND THE "HANDY CYCLE PUMP" COMPANY, OF SAME PLACE.

BICYCLE-PUMP.

SPECIFICATION forming part of Letters Patent No. 624,663, dated May 9, 1899.

Application filed April 14, 1898. Serial No. 677,570. (No model.)

To all whom it may concern:

Be it known that I, HERMAN LEINEWEBER, a citizen of the United States, residing at South Chicago, in the county of Cook and State of Illinois, have invented a new and useful Improvement in Bicycle-Pumps, of which the following is a specification.

My invention relates to an improvement in the class of hand-operated pumps used for inflating pneumatic tires; and my object is to adapt the small-sized "hand-pump" to be used like the larger "foot-pump," with the efficiency of the latter, but much more easily. I accomplish this by my improved piston-rod construction, whereby it is rendered extensible and controllable to enable it to be lengthened for operation and to be folded for compactness when out of use.

Referring to the accompanying drawings, Figure 1 is a view in elevation, partly broken, of an air-pump provided with my improvement; and Fig. 2, a sectional view showing the construction of the piston-rod whereby it is rendered extensible and contractible.

A is the pump-cylinder, carrying near one end a hinged foot-bearing B and a flexible tube B', leading from the air-outlet r, and provided at its free end with a screw-nozzle p for application to the nipple of the tire to be inflated.

C is the piston within the cylinder A and having a rod D extending out through an end of the cylinder.

With the exception of the piston-rod all the parts thus far described may involve any suitable or well-known construction, or the pump may involve any construction different from that shown and described, as my invention relates only to the construction of the piston-rod, which may be used with equal advantage with any construction of pneumatic-tire pump.

The rod D is formed in sections. The section o, immediately connected with the piston, is tubular and is provided at its outer end with a stop or shoulder o'. The section n, which may be solid, as shown, and is preferably of about the same length as the tubular section, telescopes with the section o and is provided with a stop n' on its inner end to engage with the stop o' and prevent separation of the sections. Adjacent to the stop n'

the section n is provided with a screw-thread n² to be engaged by a nut n³, and on the outer end of the section n is provided a handle m. 55

To adapt the pump for use, the section n of the piston-rod is drawn out of the tubular section and fastened in its withdrawn condition by screwing the nut n³ upon the thread n² to firmly bind the two sections together. 60 In this condition the piston-rod is extended to a length or height which enhances the convenience of operating it.

To contract the piston-rod into the desired compact form for convenience in carrying it, 65 the nut n³ is unscrewed from the thread n², when the section n may throughout its entire unthreaded length slip through the nut and be introduced telescopically into the section o.

With my improvement the ordinary small hand-pump (that shown in the drawings is nearly full size) may be used as effectively as the well-known so-called "foot-pump" and much more conveniently and easily. 70

While the nut and thread means for fastening the telescoping sections of the rod in their withdrawn condition afford the best means for the purpose, I desire to include as within my invention any analogous means for the purpose involving a male thread on one of the 80 piston-rod sections and to coöperate therewith an internally-threaded socket on the other section.

What I claim as new, and desire to secure by Letters Patent, is— 85

1. In a bicycle-pump, the combination of a piston-rod formed of a tubular section o and a section n telescoping therewith and having a thread n², said sections being held together against separation by withdrawal, and a nut n³ on the threaded section, substantially as and for the purpose set forth.

2. In a bicycle-pump, the combination of a piston-rod formed of a tubular section o having a stop o' near its outer end, and a section n telescoping with said tubular section and having a stop n' on its inner end and a thread n², and a nut n³ on the threaded section, substantially as and for the purpose set forth. 95

HERMAN LEINEWEBER.

In presence of—

R. T. SPENCER,
DAN W. LEE.
